CLAIM

The ornamental design for a fishing reel handle, as shown and described.

DESCRIPTION

FIG. 1 is a top, front and right side of the perspective view of a fishing reel handle showing our new design;

FIG. 2 is a front elevational view thereof;

FIG. 3 is a right side elevational view thereof;

FIG. 4 is a top plan view thereof; and,

FIG. 5 is a bottom view thereof.

The broken line showing of knobs in FIGS. 1-5 is for illustrative purposes only and forms no part of the claimed design.
